GAS BURNER

Fred William Cohrs, Calgary, Alberta, Canada

Application August 6, 1937, Serial No. 157,640
In Canada July 23, 1937

2 Claims. (Cl. 158—99)

My invention relates to gas burners of an improved type, and the objects of my invention are to provide a burner that is considerably more efficient and more economical in point of gas consumption than those of existing types, and one that, whilst conventional in principle, is radically different in design and resultant performance.

This invention embodies a mixing chamber to receive regulated supplies of gas and prewarmed air, a preheating of the mixed gas and air before ignition, a preheating of a regulated supply of secondary air introduced into the flame from below the flame, and an improved flame spreading means, all of which substantially increases the thermal efficiency of this gas burner.

In further explanation of the advantages of this burner over other types, I have adopted the principle of allowing the air and gas to mix for combustion purposes in the abovementioned mixing chamber before entering the passage-way leading to the burner, in preference to injecting the gas from the main directly into the said passage-way and sucking the air supply for combustion purposes from behind the gas nozzle.

I attain these objects by the device illustrated in the accompanying drawing, in which:

Fig. 1 shows a view of the gas burner in elevation and partly sectional in a fragmentary manner.

Fig. 2 shows a half plan view.

1 represents a gas nozzle with supply aperture 2 entering a T-shaped gas and air mixing chamber 3. The said chamber 3 forms a base or supporting element for the gas burner generally. Air intakes 4 are attached to the two straight through openings of the said T-piece 3, and in the case of a vertical burner project upwardly towards each side of the combustion chamber as later referred to. A nipple 5 is securely attached to the up-turned branch 3a of the said T-piece 3 and forms a passage-way for the mixed gas and air to the burning element. This nipple 5 is also threaded at its upper end to connect with the base 6 of a bowl-shaped combustion chamber 7, said chamber 7 forming the enclosing member of the heating elements. The lip of the said chamber curves outwardly as shown at 8 and the wall circumvents the heating elements to form the said combustion chamber. The heating elements referred to consist of an inverted cup shaped mantle 9 internally supported by and affixed to posts 10, said posts 10 being vertically attached to a lower threaded ring 11 in such a manner as to leave considerable

clearance between the said ring and the mantle 9 for the flow of the gases. The said ring is screwably attached to a vertically disposed main gas stand pipe 12 the said pipe being threaded for this purpose. This pipe is also threaded at its lower end to connect into the base 6 of the bowl shaped member 7. Thus a continuous passage-way for the gases is provided through the mixing chamber 3, the nipple 5 and the stand pipe 12, the upper end of the stand pipe forming 10 the port outlet at 13 for the mixed air and gas prior to ignition. The burner elements are disposed concentrically with respect to the bowl 7. The post supported mantle 9 may be raised or lowered for regulation of the flow of gases from the port 13 by turning the mantle 9 as desired. Below the said mantle 9 and distanced therefrom is a circular horizontal baffle or flame spreading plate 14 concentrically attached to the stand pipe 12. The gases strike this plate 14 and are ignited, 15 the flame being diverted outwards and upwards. The amount of annular space between the mantle 9 and the baffle plate 14 is adjusted by rotating the mantle 9 with the ring 11 towards or away from the said fixed plate 14. Holes 15 in 20 the lower part of the bowl 7 permit the entry of a secondary supply of air, which air is regulated as necessary in amount for proper combustion by a cover plate 16 similar in contour to the lower part of the said bowl 7 and disposed concentrically about the outer face of the dished lower portion of the said bowl. This cover 16 is screwably mounted on the nipple 5 upon which it may be raised or lowered for secondary air regulation. At the junction of the upper wall of the chamber 25 7 and the dished bottom of the said chamber a horizontal flange 17 projects outwardly around the circumference of the chamber. The purpose of this flange is to assure a maximum amount of heating surface for raising the temperature of 30 the air inflow into the intakes 4 situated just underneath. Regulation of the air into these intakes 4 is maintained by any suitable means such as that shown at 18, which consists of a washer 19 mounted on the intake flange by an 35 off centered set screw 20.

The flow performance is as follows: Gas from the main flows to the gas nozzle in the usual way under pressure and enters the mixing chamber 3. At this point air is drawn into this mixing chamber through the air intakes 4 due to velocity of gas flow up the nipple 5 and the stand pipe 12. This air is warmed as the elements of the burner become heated. The gases pass out of this stand pipe to strike the adjustable mantle 40 45 50 55

9 which acts as a baffle plate to divert the gas flow downward to strike the lower diverting baffle plate 14 where ignition takes place. The flame here spreads from the open end of the 5 said mantle and rises up within the combustion chamber 7. It is during the passage of gases through the stand pipe 12 and the mantle 9 that preheating of the gases occurs, which fact is taken fullest advantage of and is an important 10 feature in this invention. When the gases are once ignited the stand pipe and mantle attain a very high degree of temperature which super-heats the flowing gases prior to actual ignition. Secondary warmed air enters the combustion 15 chamber 7 through the holes 15 and at a raised temperature mixes with the ignited gases to further increase the thermal efficiency of the burner. As a precaution against a red hot condition of the wall of the chamber 7 a lining of 20 asbestos is added around the flame contact surfaces of the said chamber.

What I claim as my invention and desire to secure by Letters Patent, is—

1. A gas burner of the type described comprising a gas cock, a gas and air mixing chamber to receive gas from the said cock, air intake pipes entering said mixing chamber, means for the control of air supply through the said pipes, a stand pipe leading directly from the said mixing 25 chamber for conveyance of gases to an outlet port, a mantle adjustably attached to the said

stand pipe and enveloping the said outlet port to invert the gas flow for emission below the gas port level, a flame spreading baffle plate attached to the said stand pipe below and distanced from the said adjustable mantle, an open end combustion chamber enclosing the terminal burner elements for upward diversion of the gas flame, an outer flange circumventing the said chamber for prewarming the inflowing air supplies, air 10 passage-ways in the dished bottom of the said combustion chamber, and means for air supply regulation through the said air passage-ways. 5

2. The combination in a gas burner of the type described of a gas cock, a gas and air mixing chamber to receive the said cock, controlled 15 air intakes delivering air into the said mixing chamber, a flame heated stand pipe for conveying the gases from the said mixing chamber and terminating in a gas outlet port, an adjustable flame heated mantle curtaining the said 20 outlet port to invert the gas flow for emission below the level of the said gas port, a flame spreading baffle plate below the lip of the said mantle, an open top combustion chamber enclosing the terminal burner elements, air passage- 25 ways in the dished bottom of the said combustion chamber, means for air supply regulation through the said air passage-ways, and an outer flange circumventing the said combustion chamber for preheating the inflowing air supplies. 30

FRED WILLIAM COHRS.
